UNITED STATES PATENT OFFICE.

WILLIAM J. HAMEL, OF OSWEGO, NEW YORK, ASSIGNOR OF ONE-HALF TO
FRANK PARKER, OF SAME PLACE.

FLUE-SCRAPER.

SPECIFICATION forming part of Letters Patent No. 507,812, dated October 31, 1893.

Application filed March 6, 1893. Serial No. 484,671. (No model.)

To all whom it may concern:

Be it known that I, WILLIAM J. HAMEL, of Oswego, in the county of Oswego, in the State of New York, have invented new and useful 5 Improvements in Flue-Scrapers, of which the following, taken in connection with the accompanying drawings, is a full, clear, and exact description.

This invention relates to the class of flue-scrapers which are provided with scraper-blades adapted to enter into the flue and expansible circumferentially to conform to the diameter of the flue and maintain contact with the inner surfaces thereof while operated 10 in the flue; and the invention consists in an improved construction and combination of the constituent members of the flue-scraper as hereinafter described and set forth in the claims.

20 In the annexed drawings Figure 1 is a side view of a flue scraper embodying my invention. Fig. 2 is a longitudinal section of the same. Fig. 3 is a transverse section on line, x, x , Fig. 1, and Fig. 4 is an end view of the 25 same.

My improved flue scraper consists essentially of the mandrel— a —, the scraper-blades— b — b — pivoted to opposite sides of the mandrel, as shown at o , and of segmental shape 30 in cross section and tapered from the front or scraping ends rearward, and the sleeve— c — journaled on the mandrel and provided with the eccentric grooves— c' — c' — as shown in Fig. 3 of the drawings, which grooves engage the rear ends of the blades— b — b — as clearly shown in Fig. 2 of the drawings, said engagement causing the scraper blades to be 35 expanded and contracted by the rotation of the sleeve— c — upon the mandrel.

40 To facilitate the operation of assembling the aforesaid constituent members of my flue scraper I resort to the following detail construction and combinations of the parts of said members. The mandrel— a — I form 45 with a journal— a' — and with the screw-threaded end portions— a'' — a'' . Upon the front end portion of the mandrel I screw a head— h — which is provided with a screw-threaded socket— h' — for the reception of 50 the screw-threaded end of the mandrel. The

sleeve— c — is smooth bored and slipped on to the mandrel from the rear end thereof until it abuts against the rear end of the socket— h' — as shown in Fig. 2 of the drawings. Said sleeve is thus seated on the journal bearing— a' — of the mandrel and it is retained on the said journal bearing by means of the ferrule— d — screwed on to the rear end of the mandrel, said ferrule being of sufficient length to permit a suitable handle— f — to be secured therein. The end of the sleeve— c — adjacent to the head— h — is formed with the eccentric grooves— c' — c' — and in order to reduce the cost of the manufacture of said sleeve I form the outer walls of the aforesaid 65 grooves in a separate ring— i — seated in a rabbet formed on the exterior of the sleeve, said ring being rigidly secured to the sleeve by a pin or pins— l — passing through the ring and side of the sleeve, the inner side of 70 the said ring being formed with eccentric rabbets constituting the outer walls of the eccentric grooves— c' — c' —, the inner walls of said grooves being formed by corresponding eccentric rabbets on the exterior of the sleeve. The 75 rear ends of the scraper blades— b — b — are inserted in the aforesaid eccentric grooves, and by turning the sleeve— c — the engagement of said grooves with the scraper blades causes the same to be expanded or contracted according to the direction in which the sleeve is turned, and in this manner the scraper is 80 adjusted to the internal diameter of the flue to be cleaned so as to be maintained in contact therewith while the scraper is operated 85 or moved longitudinally in the flue. The thin front edges of the scraper blades effectually clean the flue during the aforesaid operation.

What I claim as new, and desire to secure 90 by Letters Patent, is—

1. The improved flue-scraper consisting of the mandrel— a —, the scraper-blades— b — b — pivoted to the sides of said mandrel and of segmental shape in cross-section and tapered from their front or scraping ends rearward, and the sleeve— c — journaled on the mandrel and provided with the eccentric grooves— c' — c' — engaging the rear ends of the blades and expanding and contracting the 100

scraper-blades by the rotation of the sleeve as set forth.

2. The combination of the mandrel —a— formed with the journal —a'— and screw-threaded end-portions —a''—a''—, the head —h— provided with the screw-threaded socket —h'— and secured thereby to the front end of the mandrel, the sleeve —c— embracing the aforesaid journal and formed with the eccentric grooves —c'—c'—, the ferrule —d— screwed onto the rear end of the mandrel, and

the scraper-blades —b—b— pivoted to the sides of the head —h— and having their rear ends seated in the grooves —c'—c'—, substantially as described and shown. 15

In testimony whereof I have hereunto signed my name this 23d day of February, 1893.

WILLIAM J. HAMEL. [L.S.]
